signors to Titeflex, Inc., a corporation of New
Jersey

Application July 19, 1941, Serial No. 403,166

21 Claims. (Cl. 123—148)

This invention relates to the radio shielding of the ignition of an internal combustion engine.

One of the main objects of the invention is to provide a shielding for the ignition conductors of the engine which shall be simple and perform its functions in an efficient manner.

A further object of the invention is to render of less weight the radio shielding of the ignition of an internal combustion engine.

A further object of the invention is to support the shielding means upon the engine in an improved manner.

A further object of the invention is to provide shielding means for ignition conductors which shall be readily applied and flexible in its application to an engine.

Other and ancillary objects of the invention will appear hereinafter.

In the accompanying drawings which illustrate the invention—

Fig. 1 is a view in front elevation, and of somewhat schematic character, illustrating an engine with ignition shielding embodying the present invention;

Fig. 2 is a similar view of a modified construction of which only a portion is illustrated, and some of the parts are broken away;

Fig. 3 is an end elevation of the junction box viewed on the line 3—3 of Fig. 1, the spark plug leads being shown in cross section;

Fig. 4 is an elevation of the end of the junction box opposite that of Fig. 3, the spark plug leads being shown in section; and

Fig. 5 is a side elevation, partly in section and on an enlarged scale, of one form of a radio shielding spark plug lead conduit with a section of an ignition conductor therein.

Referring to the drawings, and first to Figs. 1, 3 and 4, the reference characters 81 to 89, inclusive, respectively designate the cylinders of an internal combustion radial cylinder engine of the type commonly used on aeroplanes, and there are casings 110 to 127 for the valve operating push rods as is well understood in connection with such engines. Also the engine has the usual crank shaft 25.

Each of the cylinders has a suitable spark plug within the metal radio shielding housings 71 to 79 respectively.

To supply ignition current, a metal radio shielding conduit 128 extends from the metal radio shield about a magneto at the rear of the engine to the metal elbow 60 removably secured to the conduit 128 by a swivel screw nut 129. The metal conduit 128 is preferably a flexible, corrugated, metal tube as shown in the patent to Brinkman, No. 1,340,818. In place of such flexible tube the conduit 128 might, under some circumstances, be a rigid tube or a tube partly rigid and partly flexible.

The lower end of the elbow 60 is flared out to form the top of a metal junction box J3 into which the elbow opens, the back of the junction box being formed by the metal plate 130, and the front of the junction box is a metal plate 131. The box has a suitable metal bottom and metal ends and the top corners of the box are flattened to form the portions 132 and 133. The box is secured by any suitable mechanical means to the push rod casings 110 and 127, and the front of the box is removably secured in position by means of screws 134.

In one end wall of the junction box are secured screw nipples to which are respectively detachably secured the metal spark plug lead conduits 66, 67 and 68 by means of swivel screw nuts, the same as 129 shown in Fig. 3. In the other end of the junction box are secured screw-threaded nipples to which the metal spark plug lead conduits 62, 63, 64 and 65 are respectively secured by similar screw swivel couplings. In the flattened top portions 132 and 133 are secured screw-threaded nipples which are respectively secured to the metal spark plug lead conduits 69 and 70. The other ends of the spark plug lead conduits 61 to 69 inclusive are respectively detachably connected with the spark plug metal radio shielding housing 71 to 79 by swivel screw-threaded couplings as referred to.

Where necessary the spark plug lead conduits may be secured to one or more push rod casings. Thus, the conduits 66 and 67 are secured to the casing 125 by a clamp 135, and the conduits 64 and 65 are secured to the push rod casing 115 by a clamp 136.

The conduits 61 to 69, inclusive, may be of stiff metal pipe, but preferably each is flexible and may be such a flexible metal tube as is disclosed in the Brinkman Patent No. 1,198,392 (see Fig. 7 thereof). If desired a braided covering of metal strips may be applied to this tube to form a structure as disclosed in the Brinkman Patent No. 1,340,818 with reference to Fig. 5 thereof; or each of the spark plug lead conduits might be of rigid and flexible sections, such a structure being shown in Fig. 5 wherein is shown a stiff, metal pipe having secured by soldering or other suitable means, to each of its ends a section T of flexible, metal pipe which may be of the construction of the Brinkman flexible, corrugated, metal tube

just referred to. The other ends of the sections T are secured, by soldering or other suitable means, to couplings including swivel nuts 184 and 186 by which the conduits are detachably secured to the shielding housing for the spark plug and the junction box respectively.

The engine shown is of the radial type and has the usual nine cylinders with one spark plug per cylinder, and consequently nine conductors are required to carry current from the magneto to the spark plugs. The nine conductors, each of which is simply a copper wire as 181 covered with insulation 188 (see Fig. 5), in the usual manner, proceed from the magneto at the rear of the engine through the conduit 128 and the elbow 88 into the junction box at the front of the engine. Thence the conductors separate each individually proceeding out of the junction box into its respective conduits 81 to 88 and therethrough to the spark plug to which the wire of the conductor is connected in any suitable or well understood manner.

It will be seen that the hereinbefore described construction provides a structure which is light in weight, which is of great importance in connection with aeroplane engines, and moreover is simpler and more readily adjustable to efficiently perform its work.

It will be noted that in place of the usual heavy manifold extending for the greater part of the distance about the shaft (the manifold is by far the heaviest part of the shielding system) applicant employs simply a small junction box as a terminal for his conduit from the magneto or other source of supply, the individual spark plug lead conduits extending for the greater portion of the distance from the spark plug to the conduit from the magneto. These individual spark plug lead conduits are more flexible as to their disposition to suit the circumstances of a given case and may be curved about the axis of the engine to reach cylinders remote from the junction box, as for instance the conduits 84, 85, 86 and 87. The whole shielding system is thus made more flexible and is lighter in weight.

Referring now to Fig. 2, the structure therein shown is suitable for service with a dual ignition system, that is one having two sets of spark plugs and a magneto or other suitable source of current for each set or system, and each of the cylinders having a spark plug of each of the systems, one plug being usually at the rear and the other at the front of the cylinder. Thus, in the apparatus of Fig. 2 the radio shielding conduit 88' from the magneto terminates in a junction box J₅ similar to the junction box J₄, while the radio shielding conduit 88" from the magneto terminates in a junction box J₄, the same as the box J₅. It will be seen that these junction boxes are symmetrically mounted with relation to the vertical plane of the axis of the device.

Inasmuch as the conductors from each magneto conduit and junction box must be distributed to the spark plugs of all the nine cylinders, some of the ignition conductors will pass from the junction box J₅ through the junction box J₄ and also the conductors will pass from the junction box J₄ through the junction box J₅. To permit this an omnibus radio shielding conduit 90, is provided through which conductors passing between the junction boxes J₄ and J₅ may pass and also individual spark plug lead conduits may take off from the conduit 90 itself. Such conduit 90 has but a single bore carrying all the wires which extend between the two junction boxes and

also any wires which may take off from the omnibus conduit itself. The ends of the conduit 90 open into the interiors of the junction boxes J₄ and J₅. Thus both the magnetos are connected through the radio shielding spark plug lead conduits 18 and 11 with the spark plugs of the top cylinder, through the spark plug lead conduits 12 and 13, with the next cylinder to the right by the similar conduits 14 and 15, to the spark plugs of the next cylinder by similar conduits 87 and 88 and to the spark plugs of the next cylinder by the similar conduits 88' and 88. The cylinder to the left of the upper cylinder has its spark plugs connected by the radio shielding spark plug lead conduits 16 and 17, the spark plugs of the next cylinder are connected through the similar conduits 18 and 19, the spark plugs of the next cylinder are connected through the similar conduits 20 and 21 and the spark plugs of the next cylinder are connected through the similar conduits 88' and 88.

While the invention has been illustrated in what are considered its best applications it may have other embodiments without departing from its spirit and is not, therefore, limited to the structures shown in the drawings.

What is claimed is:

1. In radio shielding for an internal combustion engine the combination with an internal combustion engine having a plurality of cylinders and spark plugs therefor, of a radio shielding conduit from a source of ignition current supply, a radio shielding junction box forming a terminal for said conduit and individual flexible radio shielding spark plug lead conduits extending from said junction box, said junction box extending for a small portion of the distance over which the spark plugs are distributed, and certain of said spark plug lead conduits extending from said junction box across at least two of said cylinders and being separately supported, and ignition conductors for said spark plugs in said conduits and junction box.

2. In radio shielding for an internal combustion engine the combination with an internal combustion engine having a plurality of cylinders and spark plugs therefor, of a radio shielding conduit from a source of ignition current supply, a radio shielding junction box forming a terminal for said conduit and individual flexible radio shielding spark plug lead conduits extending from said junction box, said junction box extending for a small portion of the distance over which the spark plugs are distributed, and certain of said spark plug lead conduits extending in opposite directions from the ends of said junction box across at least two of said cylinders and being separately supported, and ignition conductors for said spark plugs in said conduits and junction box.

3. In radio shielding for an internal combustion engine the combination with an internal combustion engine having a plurality of cylinders and spark plugs therefor, of a radio shielding conduit from a source of ignition current supply, a radio shielding junction box forming a terminal for said conduit and individual flexible radio shielding spark plug lead conduits extending from said junction box, said junction box extending for a small portion of the distance over which the spark plugs are distributed, and certain of said spark plug lead conduits extending from said junction box across at least two of said cylinders, being separately supported and conforming to the contour of said engine and

ignition conductors for said spark plugs in said conduits and junction box.

4. In radio shielding for an internal combustion engine the combination with an internal combustion engine having a plurality of cylinders and spark plugs therefor, of a radio shielding conduit from a source of ignition current supply, a radio shielding junction box forming a terminal for said conduit and individual flexible radio shielding spark plug lead conduits extending from said junction box, said junction box extending for a small portion of the distance over which the spark plugs are distributed, and each of certain of said spark plug lead conduits extending from said junction box across at least two of said cylinders and individually secured to said engine at a point intermediate its ends and between the junction box and the cylinder, the spark plug of which is served by the conduit and ignition conductors for said spark plugs in said conduits and junction box.

5. In a radio shielding for an internal combustion engine the combination with an internal combustion engine having cylinders, spark plugs therefor, valve push rods and casings therefor, of a radio shielding conduit from a source of ignition current supply, a radio shielding junction box forming a terminal for said conduit, and individual flexible radio shielding spark plug lead conduits extending from said junction box, said junction box extending for a small portion of the distance over which the spark plugs are distributed, each of certain of said spark plug lead conduits extending across at least two of said cylinders and being individually secured to certain of said push rod casings and ignition conductors for said spark plugs in said conduits and junction box.

6. In a radio shielding for an internal combustion engine the combination with an internal combustion engine having cylinders, spark plugs therefor, valve push rods and casings therefor, of a radio shielding conduit from a source of ignition current supply, a radio shielding junction box forming a terminal for said conduit, and individual radio shielding spark plug lead conduits extending from said junction box, said junction box extending for a small portion of the distance over which the spark plugs are distributed, said junction box being secured to certain of said push rod casings.

7. In a radio shielding for an internal combustion engine the combination with an internal combustion engine having cylinders, spark plugs therefor, valve push rods and casings therefor, of a radio shielding conduit from a source of ignition current supply, a radio shielding junction box forming a terminal for said conduit, and individual radio shielding spark plug lead conduits extending from said junction box, said junction box extending for a small portion of the distance over which the spark plugs are distributed, said junction box being secured to push rod casings of adjacent cylinders.

8. In a radio shielding for an internal combustion engine the combination with a radial cylinder, internal combustion engine having spark plugs, valve push rod casings, and a main shaft, of a radio shielding conduit from a source of ignition current supply, a radio shielding junction box forming a terminal for said conduit and individual flexible radio shielding spark plug lead conduits extending from said junction box, said junction box extending for a small portion of the distance over which the spark plugs are dis-

tributed, certain of said spark plug lead conduits extending from said junction box across a plurality of at least two of said cylinders and being separately supported, and certain of said spark plug conduits being curved to pass about said shaft and ignition conductors for said spark plugs in said conduits and junction box.

9. In a radio shielding for an internal combustion engine the combination with an internal combustion engine having a plurality of cylinders, spark plugs therefor, a main shaft and push rods and valve push rod casings, of a radio shielding conduit from a source of ignition current supply, a radio shielding junction box forming a terminal for said conduit, said junction box being secured upon certain of said push rod casings and individual radio shielding spark plug lead conduits extending from said junction box and secured to certain other of said push rod casings.

10. In a radio shielding for an internal combustion engine the combination with an internal combustion engine having a plurality of cylinders, spark plugs therefor, a main shaft, valve push rods and valve push rod casings, of a radio shielding conduit from a source of ignition current supply, a radio shielding junction box forming a terminal for said conduit, said junction box being secured to push rod casings upon different cylinders.

11. In a radio shielding for an internal combustion engine the combination with an internal combustion engine having a plurality of cylinders and spark plugs therefor, of a plurality of radio shielding conduits through which current is supplied to said spark plugs, radio shielding junction boxes forming terminals for said conduits, an omnibus radio shielding conduit having a single bore connecting said junction boxes and individual radio shielding spark plug lead conduits individually supported and extending from said junction boxes.

12. In a radio shielding for an internal combustion engine the combination with an internal combustion engine having a plurality of cylinders and spark plugs therefor, of a plurality of radio shielding conduits through which current is supplied to said spark plugs, radio shielding junction boxes forming terminals for said conduits, an omnibus radio shielding conduit having a single bore connecting said junction boxes and individual radio shielding spark plug lead conduits individually supported and extending from said omnibus conduit.

13. In a radio shielding for an internal combustion engine the combination with an internal combustion engine having a plurality of cylinders and spark plugs therefor, of a plurality of radio shielding conduits through which current is supplied to said spark plugs, radio shielding junction boxes forming terminals for said conduits, an omnibus radio shielding conduit having a single bore connecting said junction boxes and individual radio shielding spark plug lead conduits extending from said junction boxes and said omnibus conduit.

14. The combination with an internal combustion engine having a plurality of cylinders and spark plugs therefor, of a radio shielding conduit from a source of ignition current supply, a radio shielding junction box forming a terminal for said conduit and individual flexible radio shielding spark plug lead conduits extending from said junction box, said junction box extending for a small portion of the distance over which the spark plugs are distributed, and certain of said spark

plug lead conduits extending from said junction box across at least two of said cylinders and being separately supported, and ignition conductors for said spark plugs in said conduits and junction box, said junction box being rectangular in cross section in a plane perpendicular to the plane of the engine cylinders.

15. The combination with an internal combustion engine having a plurality of cylinders and spark plugs therefor, of a radio shielding conduit from a source of ignition current supply, a radio shielding junction box forming a terminal for said conduit and individual flexible radio shielding spark plug lead conduits extending from said junction box, said junction box extending for a small portion of the distance over which the spark plugs are distributed, and certain of said spark plug lead conduits extending from said junction box across at least two of said cylinders and being separately supported, and ignition conductors for said spark plugs in said conduits and junction box, said junction box having a substantially flat side substantially parallel to the plane of the engine cylinders, said flat side being separate from the remainder of said box and means for removably securing said side to the remainder of said box.

16. The combination with an internal combustion engine having a plurality of cylinders and spark plugs therefor, of a radio shielding conduit from a source of ignition current supply, a radio shielding junction box forming a terminal for said conduit and individual flexible radio shielding spark plug lead conduits extending from said junction box, said junction box extending for a small portion of the distance over which the spark plugs are distributed, and certain of said spark plug lead conduits extending from said junction box across at least two of said cylinders and being separately supported, and ignition conductors for said spark plugs in said conduits and junction box, said junction box having a plurality of substantially flat sides substantially parallel to the plane of the engine cylinders, said sides being separate from the remainder of the box and means for removably securing each of said flat sides to the remainder of the box.

17. The combination with an internal combustion engine having a plurality of cylinders and spark plugs therefor, of a radio shielding conduit from a source of ignition current supply, a radio shielding junction box forming a terminal for said conduit and individual flexible radio shielding spark plug lead conduits extending from said junction box, said junction box extending for a small portion of the distance over which the spark plugs are distributed, and certain of said spark plug lead conduits extending from said junction box across at least two of said cylinders and being separately supported, and ignition conductors for said spark plugs in said conduits and junction box, the outward side of said box away from the said engine cylinders being substantially flat and separate from the remainder of the box and means for removably securing said flat side to the remainder of the box.

18. The combination with an internal combustion engine having a plurality of cylinders and spark plugs therefor, of a radio shielding conduit from a source of ignition current supply, a radio shielding junction box forming a terminal for said conduit and individual flexible radio shielding spark plug lead conduits extending from said junction box, said junction box extending for a

small portion of the distance over which the spark plugs are distributed, and certain of said spark plug lead conduits extending from said junction box across at least two of said cylinders and being separately supported, and ignition conductors for said spark plugs in said conduits and junction box, said junction box having a substantially flat side inwardly toward the cylinders and a second flat side on the opposite side of the box from the aforesaid side, said second side being outwardly away from the said engine cylinders, said sides being separate from the remainder of said box, means for removably securing the first mentioned side to the remainder of the box and means for removably securing the said second side to the remainder of the box.

19. The combination with an internal combustion engine having a plurality of cylinders and spark plugs therefor, of a radio shielding conduit from a source of ignition current supply, a radio shielding junction box forming a terminal for said conduit and individual flexible radio shielding spark plug lead conduits extending from said junction box, said junction box extending for a small portion of the distance over which the spark plugs are distributed, and certain of said spark plug lead conduits extending from said junction box across at least two of said cylinders and being separately supported, and ignition conductors for said spark plugs in said conduits and junction box, certain of said radio shielding spark plug lead conduits extending from the top of said junction box.

20. The combination with an internal combustion engine having a plurality of cylinders and spark plugs therefor, of a radio shielding conduit from a source of ignition current supply, a radio shielding junction box forming a terminal for said conduit and individual flexible radio shielding spark plug lead conduits extending from said junction box, said junction box extending for a small portion of the distance over which the spark plugs are distributed, and certain of said spark plug lead conduits extending from said junction box across at least two of said cylinders and being separately supported, and ignition conductors for said spark plugs in said conduits and junction box, certain of said radio shielding spark plug lead conduits extending from the top of said junction box.

21. The combination with an internal combustion engine having a plurality of cylinders and spark plugs therefor, of a radio shielding conduit from a source of ignition current supply, a radio shielding junction box forming a terminal for said conduit and individual flexible radio shielding spark plug lead conduits extending from said junction box, said junction box extending for a small portion of the distance over which the spark plugs are distributed, and certain of said spark plug lead conduits extending from said junction box across at least two of said cylinders and being separately supported, and ignition conductors for said spark plugs in said conduits and junction box, certain of said radio shielding spark plug lead conduits extending from the top of said junction box and certain other of said spark plug lead conduits extending from an end of said box.

22. The combination with an internal combustion engine having a plurality of cylinders and spark plugs therefor, of a radio shielding conduit from a source of ignition current supply, a radio shielding junction box forming a terminal for said conduit and individual flexible radio shielding spark plug lead conduits extending from said junction box, said junction box extending for a small portion of the distance over which the spark plugs are distributed, and certain of said spark plug lead conduits extending from said junction box across at least two of said cylinders and being separately supported, and ignition conductors for said spark plugs in said conduits and junction box, certain of said radio shielding spark plug lead conduits extending from the top of said junction box and certain other of said spark plug lead conduits extending from the ends of said box.
